To all whom it may concern:

Be it known that I, Finley F. Fig. 1 is a side elevation of a handle showing the design;

Fig. 2 is a plan view thereof; and

Fig. 3 is an end view.

The dominant feature of my design resides in a curved substantially rectangular handle, the edges being rounded and the two sides having shallow grooves diminishing in depth from the outer end.

I claim:

The ornamental design for a handle for knives, forks, and similar articles substantially as shown and described.

In testimony whereof, I affix my signature.

FINLEY F. ELLINGWOOD.
